UNITED STATES PATENT OFFICE

OTTO J. MOEHLER, OF NEWARK, NEW JERSEY, ASSIGNOR TO GENERAL ELECTRIC VAPOR
LAMP COMPANY, OF HOBOKEN, NEW JERSEY, A CORPORATION OF NEW JERSEY

DESIGN FOR AN ULTRA-VIOLET STERILIZING APPARATUS

Application filed November 2, 1932. Serial No. 45,711. Term of patent 14 years.

To all whom it may concern:

Be it known that I, OTTO J. MOEHLER, a citizen of the United States, residing at 113 North Ninth Street, in the city of Newark, county of Essex, and the State of New Jersey, have invented a new, original, and ornamental Design for an Ultra-Violet Sterilizing Apparatus, of which the following is a specification, reference being had to the accompanying drawings, forming a part thereof.

Figure 1 is a front elevational view of my new design for ultra-violet sterilizing apparatus,

Figure 2 is a plan view thereof, and Figures 3 and 4 are rear and side elevations thereof, respectively.

I claim:

The ornamental design for an ultra-violet sterilizing apparatus, substantially as shown.

OTTO J. MOEHLER.
